UNITED STATES PATENT OFFICE.

JAMES WESTCOTT, OF KANSAS CITY, MISSOURI.

SAFETY SWITCH MECHANISM.

SPECIFICATION forming part of Letters Patent No. 425,557, dated April 15, 1890.

Application filed April 17, 1889. Serial No. 307,628. (No model.)

To all whom it may concern:

Be it known that I, JAMES WESTCOTT, a citizen of the United States, residing at Kansas City, county of Jackson, and State of Missouri, have invented a new and useful Improvement in Automatic Safety Switch Mechanisms, of which the following is a specification.

My invention relates to that class of devices intended to be operated by contact with the forward wheels of an approaching train of cars; and the object of my invention is to guard against the possibility of said train running into a switch, left open carelessly or otherwise. I attain said object by means of the mechanism illustrated in the accompanying drawings, of which—

Figure 1 represents a diagram or plan view of an open railroad-switch, showing the main track $a'a$ and side tracks b , also the sleeves $y'y$, thrust-bars t , reach-rod e , connecting-rods A and d , crank-lever z , and switch-stand crank f . Fig. 2 shows a plan view of the actuating mechanism enlarged for the purpose of showing more distinctly the relative position of the following parts: bearings n , shaft r , spring k , rocking lever m , lug o , arm p' , hub p , and crank and pin l . Fig. 3 is an enlarged end view of a vertical section on line v v . In it will be seen the lever m and arm p' . It also shows the location of the shaft v under the rail a' .

The construction and application of my device are as follows:

In Fig. 1 will be seen rails, $a'a$ representing the main track and rails, and b the side track, all of which are secured in the usual manner to the ties and connected and operated by means of common rods c and d and the switch-stand crank f . In the diagram shown it will be evident that a train of cars going south (see meridian shown) would leave the tracks $a'a$, and, further, should a train going north remain upon the side track b and through a misunderstanding a second train should follow, there would be a possibility of a collision unless the rails of main track had been brought in line with each other.

The bringing of rails in line upon the approach of a train from either direction is the object of my invention, and I have invented

the following device to be operated by either of said trains, said device being actuated or moved by the forward wheels of said trains.

In Fig. 1 will be seen two journals n , secured to the tie w , which supports the shaft r . Fastened rigidly to said shaft may be seen crank l and hub p , having a projected arm p' . Fitted loosely upon the shaft are the spring k and rocking lever m , having a lug or lip o . One end of the spring should be secured to said arm and the other end to the tie w or journal n . This part of the mechanism should be placed at a suitable distance back from the rails $a'a$, in order that the lever m may be actuated by the aforesaid train before the weight of said train comes upon rails $a'a$. To the crank l , I next secure the reach-rod e , which in turn is connected by means of thrust-bars t to the sleeves $y'y$, fitted upon the connecting-rod d . Thus far the mechanism would be completed in one direction only from the lever m to the rod d . To make the device double acting, I duplicate each part and place them in their proper positions north of the rod d , thus providing two levers connected to the rod d . In Fig. 1 will be seen a common ground-switch stand with weighted crank-lever z , and, the same being an old idea, I use it in connection with my invention for the purpose hereinafter described. It will be noticed that the said stand is connected to the sleeve y' by means of rod A .

The object of the several parts described is as follows: journals n to secure that part of the mechanism to the tie w , lever m to receive the motion from the train, and spring k to retain said lever and lug o against the arm p , and also to allow a train to pass over or depress the lever in a backward direction. The functions of arm p' , hub p , shaft r , and crank l are to transmit the motion of the lever m to the rod e . The use of the rod e is to carry motion over the distance from m to the bars t , which are pivoted to the said rod and used to actuate the sleeves $y'y$, said sleeves moving the rod d and rails $a'a$, the stand or lever z providing means of depressing arm p' , as herein-after described.

Having mentioned and described the several parts and their functions, I will notice the

principal operations attendant upon the use of my device. First, to depress the arm p' by means of lever z and to retain it so depressed during the passage of the train from the main onto the side track; second, to depress the lever m for the purpose of bringing the rails in line with each other; third, to depress the arm p' by means of crank f when the rails are in line or when the main track is clear; fourth, to arrange the handle h so as to prevent it from being locked in any other position than h' , or when the main line of rails are in position.

The actual operation of my device would be as follows:

First. Presuming the switch to be left open, as shown, by carelessness or otherwise, it will be evident that when a train is going north, the forward wheel would strike the lever m , which is close to and projects above the rail, (see Fig. 3,) and thus depress said lever. The lug o engaging the arm p' , and carrying with it crank l , which thus moves the rod e in direction of the arrow, the bars tt would receive the forward thrust of said rod, and as the rod A is on the center line of the crank-lever z and connected to the sleeve y' , said sleeve would be immovable, and sleeve y would be forced directly east and would carry with it the rod d' and rails $a' a'$, thus bringing them in line and allowing the train to pass the switch in safety. It will here be noticed that the handle h in the meantime would have returned to the position h' , and, further, that the same cause and effect would have been produced if the several parts were du-

plicated and placed in position to receive movement from a train going south.

Second. In order to prevent a train (intending to go upon the side track) from striking the lever m , it would be necessary that the person turning the switch should remain and raise the lever z to nearly a vertical position, which would move the sleeve y' and draw rod e forward, and thus depress arm p' , which would allow spring k to depress lever m , keeping it in contact with said arm. Sleeve y' should be set at a proper distance from the end of the rod d , so as to prevent lever z from reaching or passing a vertical position, as it would when released return by gravity to a horizontal position.

Knowing that there are other devices for a similar purpose, I hereby state that which I claim as new and desire to secure by Letters Patent—

1. In an automatic switch-operating device, the rigid and sliding sleeves fitted upon a common connecting-rod d , in combination with thrust-bars t and suitable connecting mechanism with the lever m , substantially as set forth and described.

2. In a railroad-switch-operating mechanism, the thrust-bars t , pivoted to a reach-rod e and adapted to work from either side of rod d , in connection with sleeves $y y'$, and in combination with the other actuating mechanism, as herein shown and described.

JAMES WESTCOTT.
